GARMENT HANGER

Margaret M. Brock, New York, N. Y.

Application May 4, 1953, Serial No. 352,754

4 Claims. (Cl. 223—89)

1

This invention relates to garment hangers, and particularly to those of the character which are telescopically collapsible or adjustable, or capable of being materially reduced in size to not only accommodate them to garments of various sizes, but to enable them to be carried or contained in small space, thus rendering them convenient for travelling.

In my Patent No. 2,547,436, dated April 3, 1951, is shown a garment hanger of this character, and the object of the present invention is to provide certain improvements thereon, and particularly relating to means by which the relatively movable parts of the hanger will retain their positions of adjustment.

More particularly, the invention contemplates the provision of a garment hanger having a frame composed of wire or metallic rod and having a central portion hung from a suspension hook and receiving end portions which are slidably adjustable toward one another on the central portion to thereby either reduce the overall size of the hanger or else extend it to full or intermediate size as required by the particular garments to be accommodated on it. The invention also contemplates the provision of means on the hanger by which a frictional engagement or braking action is provided between the relatively movable parts of the hanger to thereby always retain the same in any selected position of adjustment. In addition, stop means is provided on the hanger parts to limit the extension of the parts and enable the same to resist bending or buckling strain when a garment is accommodated on it.

With these and other objects to be hereinafter set forth, in view, I have devised the arrangement of parts to be described and more particularly pointed out in the claims appended hereto.

In the accompanying drawing, wherein an illustrative embodiment of the invention is disclosed,

Fig. 1 is a front elevation of a garment hanger constructed in accordance with the invention, and shown in its extended or fully open position;

Fig. 2 is a top plan view of the friction device or brake;

Fig. 3 is a sectional view, taken substantially on the line 3—3 of Fig. 2, looking in the direction of the arrows;

Fig. 4 is a detail view of two of the overlapped parts of the hanger, showing the stop provided on one of the parts;

Fig. 5 is a sectional view, taken substantially on the line 5—5 of Fig. 4, looking in the direction of the arrows; and

2

Fig. 6 is a sectional view taken substantially on the line 6—6 of Fig. 4, looking in the direction of the arrows.

Referring to the drawing, it will be noted that the hanger consists of a triangular frame composed of four main wire elements, namely, the central supporting member 1, the end members 2 and 3, and the suspension hook 7. All of these parts of the hanger are preferably composed of relatively stiff wire which may be bent to the desired shapes by known wire-forming machinery. The central supporting member 1 consists of a single piece of wire, and is formed with the two legs 4 and 5 extending divergently from the centrally located loop 6 which receives a loop 8 formed on the lower end of the suspension hook 7. At the free end of each of the legs 4 and 5 is formed a guide loop or eye 9, and adjacent to each of the loops or eyes 9 is provided a flattened part 10 constituting a stop for a loop 11 formed at the end of the legs 12 on each of the end members 2 and 3.

The end members 2 and 3 are both alike in construction, each of the end members consisting of a bent length of wire which may be described as being roughly U-shaped, having a lower longer leg 13 or 13a and an upper shorter leg 12. The loop or eye 11 is formed at the end of the leg 12, and at the end of the long leg is formed a laterally-bent guide loop or eye 14.

In the assembled position of the parts of the hanger, it will be observed that each of the short legs 12 on the end members 2 and 3, extends and is guided through one of the loops or eyes 9 on the legs 4 and 5 of the central member 1. It will be noted that the flattened portions 10 on each of the legs 4 and 5 act as stops or abutments for the eyes 11 as seen in Fig. 1, thus limiting the relative movement of the parts 1, 2 and 3 when they are moved to the open or distended position of the hanger, which is the position shown in Fig. 1. Also by the provision of these stops 10, the points of the engagement of the loops 10 and 11 with the legs 5 and 12 are spaced apart, so that any tendency of the upper portions of the hanger to buckle near these points is avoided.

It will be noted that the legs 4 and 5 extend respectively through the loops or eyes 10. The long leg 13 of one of the end members extends through the guide loop 14 on the companion end member, as clearly seen in Figs. 1 and 2. It will be noted from Fig. 2, that parts of the two legs 13 and 13a are overlapped, and the leg indicated at 13a carries a double-bore sleeve 15 held against longitudinal movement on the leg 13a by being positioned between two flattened

portions 16 and 17 formed on the leg 13a. The sleeve is longitudinally split as indicated at 18 to thereby provide two jaws, indicated respectively at 19 and 20, which embrace the leg 13 between them. These jaws 19 and 20 clamp the leg 13 firmly, yet the frictional pressure imposed is not sufficient to prevent the legs 13 and 13a from being relatively moved to or from one another when a certain amount of manual force is imposed upon them. The sleeve 15 thus constitutes a brake and tends to hold the legs 13 and 13a in any desired overlapping position, while also tending to materially strengthen the crossbar of the hanger, composed of the two legs 13 and 13a.

The open or extended position of the hanger is shown in Fig. 1, wherein it will be seen that the hanger, when so extended, is of the normal shape and size of the conventional wire coat hanger. When it is desired to reduce the size of the hanger or to collapse or telescope it compactly for packing it in a handbag or otherwise carrying it, the end members 2 and 3 are pushed inwardly or toward one another to either the limit of such movement or to any extent desired to reduce the hanger to the required size. The sleeve-like brake 15 will serve to hold the parts of the hanger in any adjusted position.

The hook 7 can be folded down, and when the hanger is fully collapsed it will be of very small and convenient size.

Having described one embodiment of the invention, it is obvious that the same is not to be restricted thereto, but is broad enough to cover all structures coming within the scope of the annexed claims.

What I claim is:

1. A garment hanger having a central portion comprising a wire section formed with a central loop, legs extending divergently from said loop, each of said legs having a guiding eye at its outer end, a flattened stop on each leg near said eye, a pair of end members of substantially U-shape, each end member having a first leg guided through one of the eyes and having an eye through which a leg on the central loop is guided, each member having a second leg terminating in an eye, each second leg being guided through the eye of its companion leg, and a friction-imposing sleeve embracing the second legs of said members and resisting movement of said legs axially through the sleeve.

2. A garment hanger having a pair of substantially U-shaped end portions of wire, each of said end portions having a relatively long leg, said long legs overlapping one another and having their ends slidably coupled so that said long legs can be overlapped to a selected extent, a friction-imposing sleeve fixed on one of the long legs and slidable in relation to the second long leg, each of the end portions having a short leg terminating in an eye, a central supporting member of wire having a suspension loop and divergent legs terminating in an eye, flattened stop members on the divergent legs, the short legs on the end members being guided through the eyes on the divergent legs, and the divergent legs being guided through the eyes on the short legs of the end members.

3. A garment hanger composed of a wire frame having parts relatively slidable with respect to one another to thereby increase or decrease the size of the frame, some of the parts having elements in overlapped and guided relation, a sleeve fitted on one of the parts, said sleeve having a pair of jaws embracing a second part and through which the second part is slidably disposed, said jaws applying a clamping pressure on the part disposed between them to thereby prevent inadvertent sliding movement of said part axially through the sleeve.

4. A garment hanger composed of a wire frame made up of relatively movable parts to enable the frame to be increased or decreased in size, said hanger including a bottom crossbar having overlapped parts, a sleeve fitted around said overlapping parts, one of the parts having enlargements between which the sleeve is positioned to thereby prevent sliding movement of the sleeve on said part, the second part being closely embraced by the sleeve being slidably through said sleeve, with the sleeve frictionally resisting such axial sliding movement.
